[21] Appl. No.: 674,531

[57] CLAIM

The ornamental design for a Christmas ornament, as shown and described.

DESCRIPTION

FIG. 1 is a front elevational view of a Christmas ornament showing my new design;

FIG. 2 is a right side elevational view thereof; and

FIG. 3 is a bottom plan view thereof.

The rear of the Christmas ornament is plain and unornamented.
